UNITED STATES PATENT OFFICE.

ARTHUR O. KOTT, OF JOHNSON CITY, TEXAS.

FUNNEL.

1,062,167.

Specification of Letters Patent.

Patented May 20, 1913.

Application filed April 11, 1912. Serial No. 690,075.

To all whom it may concern:

Be it known that I, ARTHUR O. KOTT, a citizen of the United States, residing at Johnson City, in the county of Blanco and State of Texas, have invented a new and useful Funnel; and I do hereby declare the following to be a full, clear, and exact description of the invention, such as will enable others skilled in the art to which it

10 appertains to make and use the same.

This invention relates to a new and useful funnel for filling a tank, bottle or other receptacle, and particularly to an automatic closing valve for the funnel, adapted to 15 close subsequently to the filling of the receptacle, at the time the receptacle is filled with its holding capacity of fluid.

The invention comprises efficient and desirable features of construction and combination of parts, as hereinafter set forth, 20 shown in the drawings and claimed.

In the drawings:—Figure 1 is a vertical sectional view of the improved funnel constructed in accordance with the invention, 25 and as applied to a receptacle. Fig. 2 is a similar view showing the valve closed, but not applied to the receptacle. Fig. 3 is a detailed view in perspective of the valve and the surrounding parts.

30 Referring to the drawings 1 designates the funnel, which is of the usual shape, in which a partition or bottom 2 having a valve seat 3 is arranged, while 4 denotes the bottle or receptacle, into which the funnel 35 extends. A collar, which is secured in position on the neck of the funnel by a thumb screw 6, is provided for limiting the insertion of the funnel in the receptacle. The collar is designated by the numeral 5.

40 Arching over the valve seat are two semi-circular guide rods 7, one on each side of the ball valve 8, to guide the valve and to prevent entire displacement of the same.

Arching over the guide rods 7, and at 45 right angles thereto is a supporting rod 9, the upper or arch portion thereof is substantially U-shaped having substantially vertical side portions 10. Pivotally mounted on the horizontal portion of the arch of 50 the supporting rod 9, is a gravitating rocking member 11, the lower end of which ter-

minates in a dished plate 12, which is adapted to embrace the ball valve and hold the same closed, when it automatically closes. The gravitating rocking member is provided with an offset bracket 13 having laterally extending arms 14, to engage the vertical sides of the arched portion of the supporting rod, to limit the upward swinging movement of the lower end of the gravitating member, when the valve is open. Pivoted to a lug 2^a of the partition 2 is a lever 15, to the short arm of which as at 16, an extension 17 of the float 18 is pivoted. When the float is in its lowermost position 55 as in Fig. 1, the long arm of the lever 15 extends partially through the valve opening, so as to hold valve 8 unseated. However, just so soon as the float raises, by the rise of the fluid in the receptacle, the long arm 60 of the lever is withdrawn from the valve opening, and by reason of the fact that, the valve 8 is constructed of heavy metal such as steel, the same automatically contacts with its seat, thereby closes the valve opening, which will cut off the flow of the fluid 65 into the receptacle. As soon as the valve 8 closes its opening, the dished end of the gravitating rocking member will engage the valve and hold the same closed. To disengage the dished end of the gravitating member, thereby release the valve from its seat, the lever 20 which is pivoted at 21 to the 70 funnel with its lower end arranged against the gravitating member, is actuated, which 75 will raise the gravitating member to the position shown in Fig. 1.

The invention having been set forth, what is claimed as new and useful is:—

In a funnel having a partition provided 90 with a valve seat and valve opening, a ball valve to coöperate therewith, guide rods arching over the seat, one on each side of the valve for preventing its displacement, a supporting rod arching over the guide rod 95 at right angles thereto and having vertical side portions, a gravitating oscillatory member suspended from the arch of the supporting rod and having a dished lower end to embrace the valve to hold the same closed, 100 and a bracket carried by the gravitating oscillatory member having laterally extend-

ing arms to engage the vertical sides of the arch of the supporting rod, a lever pivoted to the funnel with its lower end in contact with the gravitating member, for oscillating the gravitating member to release the valve, and a float actuated lever extending through said opening to unseat the valve.

In testimony whereof I have signed my name to this specification in the presence of two subscribing witnesses.

ARTHUR O. KOTT.
